CONTROL MEANS FOR FANFOLDING
MECHANISMAnthony F. Rodrigues, Los Gatos, Calif., assignor to
Cycle Equipment Company, Los Gatos, Calif., a corpora-
tion of NevadaOriginal application July 2, 1962, Ser. No. 206,942, now
Patent No. 3,182,991, dated May 11, 1965. Divided
and this application Aug. 25, 1964, Ser. No. 392,001
2 Claims. (Cl. 226—44)This application is a division of my co-pending appli-
cation Serial No. 206,942, filed July 2, 1962, for Fan
Folding Mechanism, now Patent No. 3,182,991.The present invention relates to tape receiving means
or fanfolding mechanisms for tape such as perforated
paper tape, for example, and is concerned more particu-
larly with improved control means therefor.It is an object of the invention to provide tape-receiving
means having a tape-responsive control arm movable in
either direction from its normal inactive position to effect
a control of the machine, and associated therewith con-
trol means producing an invariable control in the machine
irrespective of the direction of the movement of the con-
trol arm.A further object of the invention is to provide a tape
control arm which can be set to the desired adjusted position
on its supporting axis in accordance with the desired
position of feed of the tape to the control arm.The above and other objects of the invention are at-
tained as set forth in the accompanying specification,
taken in connection with the attached drawings, in which:

FIG. 1 is a plan view of a fanfolding machine;

FIG. 2 is a side elevational view of the fanfolding
machine, with certain parts shown in dotted lines;FIG. 3 is a detail selectional view taken as indicated
by the line 3—3 in FIG. 1;FIG. 4 is a horizontal sectional view taken as indicated
by the line 4—4 in FIG. 2;FIG. 5 is a view similar to FIG. 4 but showing other
operating positions of the linkage means.Referring first to FIGS. 1 and 2, the fanfolding ma-
chine includes a casting 20 comprising the body or frame
of the machine and the housing, and on this housing there
is mounted a pair of folding drums 21 and 22, described
in detail hereinafter, which operate with respect to paper
tape 23 fed over a control arm 24 to fanfold this tape
and to deliver it to a receiving surface 26 which forms
part of the removable or detachable tray 28. The bottom
wall 26 of this tray is apertured or slotted to admit two
conveyor belts 27 which are carried by respective sets of
sheaves 29 which are suitably driven in a direction indi-
cated by the arrow to move the fanfolded tape from the
region of the folding drums.The respective folding drums 21 and 22 are fully de-
scribed in said patent and each drum includes a folding
blade 52 which is operated either as a folding blade or a
tucking blade on alternating revolutions of the drum as
fully described in said patent. The following blade 52,
for example, as shown in FIG. 1, cooperates with a fold-
ing wall 41 having a roughened surface 42. The drums
have intermeshing gears 46, one of which is driven by a
pinion 47 from the motor shaft 48 as described in said
patent.The tape receiving means of the instant invention is a
slave machine, and operates to fold the tape only when
tape is available and stops operation when tape is not
available. In order to receive the tape advantageously
from any direction, control arm 24 (FIGS. 1, 2 and 5)
comprises a rod 106 carrying an upright shaft 107 on
which a roller 108 is mounted in conjunction with a
spring-type tape retainer 109. The rod 106 is releasably
received in a sleeve 111 and has its inner end notched to

2

embrace shaft 113. Sleeve 111 is clamped by a nut
112 and may be released so that the shaft 106 is positioned
in any desired angular position on the shaft 113 pivoted
in the frame 20.At its lower end the shaft 113 (FIGS. 1, 4 and 5) car-
ries a control segment or lever 117 having two links 118
pivoted about respective axes 119 which are symmetrically
arranged with respect to the shaft 113. Each of the
levers 118 has a slot 121 at its other end which is en-
gaged with a pin 122 at the end of a switch control lever
123 pivoted at 124. The opposite end of the lever 123
is urged counterclockwise by a spring 126 and is slotted
at 127 to engage the control arm 128 of a conventional
two-position set switch 129 for the motor 48. Thus, in
either direction of the movement of the control arm 24,
as seen, for example, in FIG. 5, the rocking of the seg-
ment lever 117 in either direction will produce the same
invariable movement of the switch lever 123 so that the
power control lever 123 enables the source of power
invariably irrespective of the direction of movement of
the control arm 24. In this way the tape can be placed
over the roller 108 extending either from the top side or
the bottom side of the view. In this way, when the tape
becomes taut and the fanfolding drums continue to feed
the tape, the control arm 24 will be moved to position
the switch 129 in its off position. When tape is available
and the spring 126 serves to return the arm 24 to its cen-
tral position, the switch will again be flipped from its
“off” position to its “on” position.While I have shown and described a preferred embodiment
of the invention, it is apparent that the invention
is capable of variation and modification from the forms
shown so that its scope should be limited only by the
proper scope of the claims appended hereto.

35 I claim:

1. In a tape feeding mechanism, a source of power,
means for enabling said source of power including a con-
trol member movable in a fixed or invariable fashion to
effect said control, a tape-sensitive control arm for con-
trolling said member mounted for movement in either
of two directions from a rest position, and a pair of links
interconnecting said arm and said member to operate
said member invariably in said one fashion irrespective
of movement of said control arm from its rest position
in either direction under the influence of the tape, said
links each having a lost motion connection with said
member and a spaced apart operation connection with
said arm.2. In a tape feed mechanism, a source of power, means
for enabling said source of power including a control
member movable in a fixed fashion to effect said control,
a tape sensitive control arm for controlling said member
mounted for movement in either of two directions from
a rest position, and linkage means interconnecting said
arm and said member to operate said member invariably
in said one fashion irrespective of movement of said
control arm from its rest position in either direction under
the influence of the tape, said linkage means includes a
lever member pivoted about an axis, a pair of links
pivotally connected to said lever symmetrically with re-
spect to said axis, and respective coinciding lost motion
connections between said links and said control member.
